UNITED STATES PATENT OFFICE.

CHRISTIAN A. PETERS, OF CINCINNATI, OHIO.

DESIGN FOR A FLOWER-EASEL.

SPECIFICATION forming part of Design No. 21,044, dated September 15, 1891.

Application filed June 12, 1891. Serial No. 396,041. Term of patent 3½ years.

To all whom it may concern:

Be it known that I, CHRISTIAN A. PETERS, a citizen of the United States, residing at Cincinnati, in the county of Hamilton and 5 State of Ohio, have invented and produced a new and original Design for an Ornamental Flower-Easel; and I do declare the following to be a full, clear, and exact description of the same, reference being had to the accompanying drawing, forming a part thereof.

My invention relates to a design for easels when they are specially prepared with ornamental supports or receivers adapted to receive flowers, and easel and such ornamental supports or receivers so arranged that when the latter are filled with flowers the whole presents a harmonious and pleasing design. The construction of this latter may be better understood by reference to the accompanying 15 drawing, in which the same is illustrated in a perspective view.

The leading feature of my design consists of an easel composed of square or rectangular bars forming in front elevation a substantially rectangular frame provided at its upper and lower cross-bars with beveled boxes and at the upright bars with S-shaped ornamental brackets, which boxes and brackets form receivers and supports for flowers.

These receivers and supports consist of boxes 30 5 and 8, supported on and between the front standards 1 1 of the easel, vases 11 11, supported on brackets 10 10, resting in sockets 9 9, also on the front standards, and chains 35 13, connecting the front standards 1 1 to the rear standard 2. The boxes are filled with earth and flowers, while flower-pots 12 12 may be set in vases 11 11. The chains are principally intended to support winding plants. The vases may, however, as well be 40 filled with cut or artificial flowers.

During the winter the easel may be taken into the house and serve as a very appropriate parlor ornament, while in the mild season of the year it is best left outside on a veranda 45 or lawn, for instance, forming thus a substitute for the flower-bed, with the additional advantage of being removable as such.

Having described my design, I claim as new—

The design for an ornamental flower-easel, as herein described and shown.

In testimony whereof I affix my signature in presence of two witnesses.

CHRISTIAN A. PETERS.

Witnesses:
